F. K. REIBIN.
VENTILATOR OPERATING DEVICE.
APPLICATION FILED AUG. 30, 1919.

Patented Nov. 9, 1920.

UNITED STATES PATENT OFFICE.

FEDOR KONSTANTINOVICH REIBIN, OF ROBSON, BRITISH COLUMBIA, CANADA,
ASSIGNOR OF ONE-HALF TO STEVE MIHALKEVICZ, OF MIDDLETOWN, CONNECTICUT.

VENTILATOR-OPERATING DEVICE.

1,358,464.

Specification of Letters Patent.

Patented Nov. 9, 1920.

Application filed August 30, 1919. Serial No. 320,943.

To all whom it may concern:

Be it known that I, FEDOR KONSTANTINOVICH REIBIN, a citizen of Russia, residing at Robson, Province of British Columbia, and 5 Dominion of Canada, have invented certain new and useful Improvements in Ventilator-Operating Devices, of which the following is a specification.

This invention has as its object the provision of means whereby the windows of a car or like structure may be opened or closed simultaneously from a single point easily accessible by the guard or conductor of the car.

15 A further object is to arrange the parts so that the windows at either the front or rear of the car may be opened without disturbing the other.

20 A further object is to provide means whereby the windows or shutters may be opened fully or partially as may be preferred and held in an adjusted position.

These and other like objects are attained 25 by the novel construction and combination of parts hereinafter described and shown in the accompanying drawings, forming a material part of this disclosure, and in which—

Figure 1 is a side elevational view showing a conventional type of car and indicating the application of the invention.

30 Fig. 2 is an enlarged side elevational view showing the operating mechanism, parts being in section in order to disclose the construction, and,

35 Fig. 3 is a transverse sectional view taken on line 3—3 of Fig. 2.

Referring to the drawings in detail, a conventional type of car is indicated by the 40 numeral 10, the same having vestibule entrances 11 at each end and is provided with a plurality of windows 12, movable vertically in the ordinary manner.

Attached to one or both of the vestibule walls 13, is a hollow conical bracket 14, having an extending hub 15, in which is threaded a sleeve 16, formed with or secured to a hand wheel 17 by which the threaded sleeve may be rotated within the hub portion of the bracket.

45 A shaft 18 extends longitudinally through the car adjacent to the sides and has fixed upon one of its ends a pair of collars 19 and 20, adapted to make contact with the opposite wall 21 of the car, the collars being spaced so that the shaft may move longitudinally a definite distance.

Formed in the end of the shaft 18, within the hub 15, is an annular groove 22 into which enters a ring 23, formed with the sleeve 16, so that as the sleeve is rotated, by means of the hand wheel, the shaft 18 is moved longitudinally within its bearings. A hub 24, formed with a lever bar 25, and having an actuating handle 26, by which it may be rotated, is pinned or otherwise rigidly engaged by the shaft so as to convey motion to it.

50 A key or spline 27 is set in the shaft 18, by which is driven a ratchet wheel 28, free to move longitudinally on the shaft, and normally pressed against the wall 13 by means of a coiled compression spring 29.

Engaged with the teeth of the ratchet wheel 28 is a spring pressed pawl 30, the same having an extending operating handle 75 31 projecting through an opening in the conical bracket 14 so as to be readily disengaged from the ratchet at any desired time. Thus the shaft 18 may be held when rotatably adjusted into a desired position.

55 Also secured upon the shaft 18 are a plurality of spur pinions 32, and 32' which are engageable with racks 33 and 33' attached to the windows in such manner that the same may be raised or lowered.

60 In operation, when it is desired to open and close the rear windows of the car, the hand wheel 17 is rotated so as to move the shaft 18 outwardly, until the collar 20 contacts with the wall 21 and the gears 32' 90 have meshed with the corresponding racks 33', whereupon the handle 26 is rotated, conveying rotary motion to the gears and operating the windows in an obvious manner.

65 If it be desired to operate the windows at the other end of the car, the hand wheel 17 is turned in the opposite direction so as to move the shaft 18 longitudinally, until the collar 19 contacts with the wall 21, causing other gears 32 to engage with the racks 33, whereupon movement will be transmitted to the windows, and due to the fact that the ratchet 28 may slide upon the shaft, it is operative with either set of the gears so that the windows may be actuated at either end of the car from the platform.

70 Having thus described my invention what I claim as new and desire to secure by Letters Patent, is—

75 1. In a window operating device, the combination with a car having a plurality of

windows slideable in a vertical plane, of a shaft rotatably journaled and movable longitudinally in said car adjacent to said windows, means for limiting the longitudinal movement of said shaft, a bracket secured to one of the end walls of said car through which said shaft passes, a sleeve screw-threaded into said bracket, means for rotating said sleeve, engaging means between said sleeve and said shaft whereby the shaft is moved longitudinally when said sleeve is rotated, means for manually rotating said shaft, a ratchet slidably engaged on said shaft, a spring-pressed detent engaged with said ratchet, means for releasing said spring-pressed detent, a plurality of pinions fixed on said shaft, and racks fixed on each of said windows, said pinions being engageable with said racks.

2. In a ventilator operating device, the combination with a plurality of ventilators, racks attached thereto, a shaft adjacent to said ventilators, pinions secured upon said shaft engageable with said racks, a bracket through which said shaft passes, a hub formed on said bracket, said hub having screw threads, a screw threaded sleeve engageable therein and connected to the shaft, means for manually rotating said sleeve whereby said shaft may be moved lengthwise, means for rotating said shaft, and means for holding said shaft when rotated, whereby the pinions of said shaft are engaged with said racks holding the same in an adjusted position. 35

In testimony whereof I have affixed my signature.

FEDOR KONSTANTINOVICH REIBIN.
